Primary Examiner — Michelle E. Wilson

Assistant Examiner — Clesse Moore, Jr.

(57) CLAIM

The ornamental design for a woman sexy nightdress, as shown and described.

DESCRIPTION

FIG. 1 is a front, left side, top perspective view of a woman sexy nightdress showing my new design;

FIG. 2 is a front elevational view thereof;

FIG. 3 is a rear elevational view thereof; and,

FIG. 4 is a right side elevational view thereof.

The broken lines depict environment that forms no part of the claimed design for the woman sexy nightdress.

1 Claim, 4 Drawing Sheets
